Maurice Druck, Lido, Long Island, N. Y.

Application November 16, 1944, Serial No. 116,362

Term of patent 7 years

(Cl. D47—6)

To all whom it may concern:

Be it known that I, Maurice Druck, a citizen of the United States of America, residing in Lido, Long Beach, county of Nassau and State of New York, have invented a new, original, and ornamental Design for a Window Curtain, of which the following is a specification, reference being had to the accompanying drawing, forming part thereof.

In the drawing:

The figure is a plan view of a window curtain embodying the design.

I claim:

The ornamental design for a window curtain, substantially as shown.

MAURICE DRUCK.
